CLAIM

The ornamental design for a combined grass trimmer and wheeled frame, substantially as shown and described.

DESCRIPTION

FIG. 1 is a front elevational view of a combined grass trimmer and wheeled frame showing my new design; FIG. 2 is a side elevational view taken from the left of FIG. 1;

FIG. 3 is a side elevational view taken from the right of FIG. 1;

FIG. 4 is a rear elevational view taken in the direction of the arrows along line 4—4 of FIG. 3, shown broken away for ease of illustration.

FIG. 1.

FIG. 2.

FIG. 3.

FIG. 4.
